UNITED STATES PATENT OFFICE.

THOMAS E. BRITTON, OF CEDAR FALLS, IOWA.

COMBINATION TRUCK AND WAGON DUMP.

1,420,078.

Specification of Letters Patent. Patented June 20, 1922.

Application filed February 17, 1921. Serial No. 445,816.

To all whom it may concern:

Be it known that I, THOMAS E. BRITTON, a citizen of the United States of America, and a resident of Cedar Falls, Blackhawk 5 County, Iowa, have invented certain new and useful Improvements in Combination Truck and Wagon Dumps, of which the following is a specification.

My invention relates to improvements in 10 combination truck and wagon dumps, particularly to tiltable dumping platforms for use in elevators or other places.

One object of my improvements is to combine in the apparatus suitable mechanism 15 for tilting the wagon platform independently, or for tilting the wagon and truck platforms together and simultaneously, and including a self-locking device appropriate to hold the platforms in any 20 position within their scope of tilting movements.

Another object of my improvements is to adapt the mechanism to automatically limit and stop the tilting movement of the 25 platforms adjustably.

Another object of my improvements is to provide means for manually initiating and controlling the movements of said mechanism, and for reversing the 30 mechanism in the returning of the platforms to their original position.

Another object of my improvements is to permit of separating driven portions of said mechanism from power-actuated driving 35 portions thereof, and the changing of position of the former to allow them to be manually actuated when necessary.

These objects have been accomplished by the means and mechanism which is hereinafter 40 described and claimed, and which is illustrated in the accompanying drawings, in which Fig. 1 is a vertical longitudinal section through the combination truck and wagon dumping platforms, showing in side 45 elevation the mechanism for controlling and tilting the platforms, the full lines showing the platforms and the mechanism at rest before tilting of the platforms downwardly, and the dotted lines showing tilted 50 position of the connected platforms with changed positions of parts of the mechanism, including the changed position of the worm-shaft when used for manually operating the tilting-means.

Fig. 2 is an under plan view of the parts 55 and mechanisms shown in said Fig. 1, the

prime motor and electric connections thereto being omitted.

Like numerals of reference denote corresponding parts in said figures.

The numeral 1 denotes a fixed elevated platform over a basement or other space, and an elongated opening 17 is provided in said platform bounded on its longitudinal sides by the framing beams 2. A pair of 60 hinged doors 9 and 10 are positioned in one end 8 of the said opening over a place of deposit below. A transverse shaft 3 crosses the opening 17 medially and has its extremities mounted in bearing-openings in 65 the beams 2.

The numeral 4 denotes a wagon platform occupying the part of the opening 17 next to the doors 9 and 10, and has longitudinal side beams 5 mounted to rock up or down 70 medially on said shaft 3, the platform being of less width than said opening 17 to afford clearance spaces for the longitudinal side beams 7 of a truck platform 6.

The truck platform is composed of the 80 forward platform portion 6 forming a continuous extension forwardly of the platform 4 and filling the forward portion of the opening 17. This portion 6 has the longitudinal side beams 7 which project 85 rearwardly therefrom as far as the rear end of the platform 4 within the clearance spaces between the platform 4 and the fixed side beams 2. The beams 7 are medially pivotally mounted on said shaft 3. 90

In order to permit of releasably connecting the two platforms together so that the wagon platform 4 may be tilted independently, or the connected platforms 4 and 6 be tilted together simultaneously, I 95 have provided a securing device, shown in Fig. 2, but which may be varied in its construction, arrangement, or position as desired. The device is shown as connecting the rear part of a platform 4 to the rear 100 ends of the side beams 7 of the truck platform 6.

This device comprises alined bolts 13 positioned across the under side of the platform 4 to slide in and out of catches 11 on 105 the under sides of the beams 7 from the bearings 12 on the under sides of the beams 5. Toggle-members 14 are pivotally connected between the inner ends of the bolts 13 and the medially located operating element 110 15 having an upturned finger passing through a short longitudinal slot 16 in the platform

4. This element 15 may be shifted longitudinally to operate the toggle-joint to connect or disconnect the bolts 13 with or from the catches 11 to lock or unlock the platform 5 4 relative to the platform 6.

At the ends of a forward cross beam of the platform 4 are bearings on which are pivoted suspended rack-bars 22. The transverse shaft 21 is rotatably mounted in bearings 20 on the frame beams 2 and carries a pair of like pinions 24 intermeshing with the racks 22, the racks being kept in engagement with said pinion by yokes 23 with included anti-friction rollers 25 bearing on the racks.

15 On one end of the shaft 21 is fixed a worm-wheel 26. The numeral 28 denotes a yoke whose ends are pivotally mounted to rock on the shaft 21 on opposite sides of said worm-wheel, and said yoke carries an integral bearing-sleeve 29 within which is rotatably mounted a worm-shaft 30 provided with a terminal worm 27 intermeshing with said worm-wheel. On the other end of the shaft 30 is fixed a belt-wheel or pulley 24, to carry 20 a belt 57 passed about a driving-pulley 56 on the rotatable shaft of a reversible electric motor 55. The numeral 31 denotes a fixed hanger open-top bearing, and the numeral 32 denotes a sleeve loosely mounted between 25 fixed collars on said shaft 30 and positioned removably in the bearing 31. A terminally looped arm 33 projects upwardly from said sleeve 32. In the platform 1 above the shaft 30 is an elongated opening 18 covered by a 30 hinged closure plate 19. When this closure plate is swung open, and the belt 57 unshipped from the pulley 34, the latter and the shaft 30 may be swung upwardly through the floor opening 18 to the erected 35 position shown in dotted lines in said Fig. 1, and in that position, the tilting of the platforms may be effected manually by 40 means of a hand crank 61 detachably coupled with the clutch-face 58 on the end of said shaft, when necessary, or at times when electric power is not available. The looped handle 33 is used to rock said shaft upwardly, and the worm 27 shifts around the circumference of the worm wheel 26 to the 45 extent of the proper arc of movement.

The numeral 41 denotes a slot cut in the fixed platform 1 medially aligned with the opening 18. At the rear end of this slot is fixed a forked spring clip 42. The numeral 38 denotes a terminally looped arm passing 55 downwardly through the slot 41 and pivoted a little above its lower end on a depending hanger 40. When rocked rearwardly in said slot, the arm 38 is received within and detachably clasped by the forks 42. Said arm 60 38 forms one member of a bell-crank lever of which the other member 37 carries a terminal brake-head 35 positioned to be rocked into or out of frictional engagement with the 65 rear part of the elongated pulley 34 below.

The numeral 48 denotes a curved depending arm fixed on one of the side beams 5 of the wagon platform 4 and carries a spaced pair of slide-bodies 43 and 50 adjustably secured thereon by means of set screws. These 70 slide-bodies carry respectively laterally directed rigid arms 44 and 49 having terminal wedges, shown at 43 and 50. Said wedges are respectively positioned rearwardly and forwardly of the arm 38. The 75 lower end of the arm 38 is continued downwardly from its pivot to serve as the movable member 52 of a make-and-break device mounted on the hanger 40 which includes conductors 53 and 54 in circuit with the reversible motor 55, and this make-and-break device is also in circuit with a source of electrical current 62 by way of the conductor 59 and a reversing switch 60.

The platform 4 or the connected platforms 85 6-6 may be tilted downwardly at the rear to permit of dumping the contents of either a wagon, or of a longer truck respectively, into the receiving opening 8 after the hinged doors 9-10 have been swung open, and then 90 the forward door 10, if propped in an inclined position, may serve as a chute.

Referring to said Fig. 1, in which the looped arm 38 is held releasably within the yieldable forked spring clip 42, it will be seen that the make-and-break arm 52 is in a position to close the circuit. To initiate 95 tilting of the platform, the switch 60 is operated manually to close the circuit through the source of electrical current 62 and the electric motor 55, starting the latter in the appropriate direction. The pulley 34, shaft 30 and worm-gear are thus rotated, the pinions 24 shifting the racks 22 upwardly to tilt the platform about its shaft 3 to lower 100 its rear end. In the descent of the arcuate arm 48 with the rear part of said platform, the wedge 43 engages either the arm 38 or a lug 51 secured thereon, and in the continued descent pushes the arm 38 forwardly 105 until it is released from the spring clip 42, when the gravity of the brake-head 35 rocks the arms 38 and 37 a further distance forwardly till the brake-head engages frictionally the pulley 34 at a time when the rearward movement of the lower member 52 has 110 opened the electric circuit through the motor. These two actions occur about simultaneously, so that the driving action of the motor ceases as the brake is applied to cause 115 instant stoppage of the tilting platform. The loop 45 on which the arm 44 and wedge 43 is mounted can be adjusted along the arcuate arm 48 to vary the scope of downward movement of the platform.

To re-elevate the platform, the arm 38 is rocked rearwardly manually to enter the spring-clip 42, and the brake-head 35 is thus lifted, while at the same time the contact arm 52 is rocked forwardly to again close 120

the circuit. Operation of the switch-device 60 may then be effected to reverse the motor 55 while starting it, and the platform is then tilted upwardly at the rear of the 5 above described power transmission mechanism. As the arm 48 moves upwardly, the lower wedge 50 engages the lug 51 on said arm 38 at the upper limit of its movement to retain the arm 38 in secured position. 10 This wedge does not prevent moving of the arm 38 past it when pushed forwardly manually.

Attention is directed to the worm-gearing in the power-transmission mechanism, which 15 is self-locking and holds the platform locked in any position in which it is stopped.

Having described my invention, what I claim as new, and desire to secure by Letters Patent, is:

20 1. A tilttable dumping platform, and means for tilting it comprising a rack mounted thereon, a pinion meshing with said rack, and self-locking mechanism including a worm and worm-wheel intermeshed there- 25 with with the worm mounted to rock about the worm-wheel and operatively connected to and adapted to rotate said pinion.

2. A tilttable dumping platform, and means for tilting it comprising like 30 racks mounted on one end thereof, a rotatable shaft, pinions fixed on said shaft and intermeshed with said racks, a worm-wheel fixed on said shaft, a rotatable worm-shaft having a worm intermeshed with said worm- 35 wheel, and mounted to swing therearound while keeping intermeshed therewith, and means reversible for rotating said worm-shaft in either of opposite directions.

3. A tilttable dumping platform, and 40 means for tilting it comprising like racks pivotally suspended from one end thereof, a rotatable shaft, pinions fixed on said shaft and intermeshed with said racks, a worm-wheel fixed on said shaft, a rotatable worm- 45 shaft having a worm intermeshed with said worm-wheel, a pulley fixed on said worm-shaft, means for rotating said pulley, and a brake for occasional frictional engagement with said pulley.

50 4. A tilttable dumping platform, and means for tilting it and controlling its movements comprising racks mounted on one end thereof, pinions intermeshed with said racks, and mechanism for simultaneously rotating 55 said pinions including elements movable from one relative position to another to use either power or manual actuation.

5. A tilttable dumping platform, and 60 means for tilting it and controlling its movements comprising mechanism operatively connected to one end thereof to tilt it downwardly or upwardly, a motor adapted to actuate said mechanism, and disconnectible elements between the other end of said plat- 65 form, and said motor adapted to automatically

discontinue the driving action of the motor on said mechanism when the platform has been tilted downwardly at its delivery end to a predetermined distance.

6. A tilttable dumping platform, and 70 means for tilting it and controlling its movements comprising mechanism adapted to tilt it up or down, and other means operatively associated with said mechanism for automatically and simultaneously both 75 stopping the mechanism and frictionally braking a rotatable element thereof in tilting the platform downwardly and including elements for occasional manual actuation in starting said mechanism in operation. 80

7. A tilttable dumping platform, and means for tilting it and controlling its movements, comprising racks mounted on one end thereof, a rotatable shaft, pinions on said shaft intermeshed with said racks, 85 a worm-wheel on said shaft, a rotatable worm-shaft carrying a worm intermeshed with said worm-wheel and mounted to be rocked about said worm-wheel, and a pulley fixed on said worm-shaft for power connection, said worm-shaft having a terminal 90 clutch-face for engagement with a detachable clutch-element for occasional manual actuation.

8. A tilttable dumping platform, and 95 means for tilting it and controlling its movements, comprising mechanism connected to one end thereof adapted to tilt it to and fro, and means, including selective groups of elements, for both stopping and braking said 100 mechanism in tilting the platform in one direction automatically, and in varying the actions of said mechanism in any adjustably regulated position of the platform.

9. A tilttable dumping platform, and 105 means for tilting it and controlling its movements, comprising a reversible electric motor in circuit with a source of electric current including make-and-break devices, mechanism operatively connected between said 110 motor and one end of said platform operable to tilt the platform to and fro, and other means connected to the other end of said platform operatively associated with one of said make-and-break devices to automatically operate said device to open said circuit when the delivery-end of the platform has 115 tilted to a dumping position.

10. A tilttable dumping platform, and 120 means for tilting it and controlling its movements, comprising an electric motor in circuit with a source of electric current including a make-and-break device, mechanism operatively connected between said motor and said platform operable to tilt the platform to and fro, and including a friction-wheel and a brake-head movable into or out of frictional engagement therewith, and other means connected to said platform adapted 125 to automatically simultaneously operate said 130

brake-head to engage said friction-wheel, and to actuate said make-and-break device to open said electric circuit when the delivery-end of the platform has arrived at either 5 limit of tilting.

11. Combined truck and wagon dumping platforms, comprising a shaft on which both 10 elements of the platforms are medially pivoted, means for disconnectibly connecting said elements together to be tilted together simultaneously or separately, and mechanism operatively connected to one of said elements, including self-locking means, for 15 tilting it to and fro.

12. Combined truck and wagon dumping platforms, comprising a shaft on which both 20 elements of the platforms are medially pivoted, means for disconnectibly connecting said elements together to be tilted together simultaneously or separately, mechanism operatively connected to one of said elements, including movable self-locking means, for 25 tilting it to and fro, and other means associated detachably with said mechanism to control and limit its action selectively, either manually in operating in either direction, or automatically by power drive in both operating it and limiting its scope of movements.

13. In combination, a tiltable body, mechanism for tilting it to and fro including a 30 rotatable element, a brake-head mounted on

a pivoted arm, said arm adapted to swing to and fro past its dead center to frictionally engage or be disengaged from said rotatable element, an arm fixed on said tiltable body, and a lug mounted adjustably upon said fixed arm adapted to releasably engage said pivoted arm to push it over its dead center to swing into frictional engagement with 35 said rotatable element when said tiltable body is tilted downwardly.

14. In combination, a tiltable body, electrically-operated mechanism for tilting it to and fro including a rotatable element, a 40 brake-head mounted on a pivoted arm, said arm adapted to swing to and fro past its dead center to frictionally engage or be disengaged from said rotatable element, an arm fixed on said tiltable body, a lug mounted 45 adjustably upon said fixed arm adapted to releasably engage said pivoted arm to push it over its dead center to swing into frictional engagement with said rotatable element when said tiltable body is tilted downwardly, and means for interrupting the action of said electrically operated mechanism 50 adapted to be actuated by said pivoted arm when it is swung in one direction by said lug on said fixed arm.

Signed at Waterloo, Iowa, this 14th day of Feb., 1921.

THOMAS E. BRITTON.
